UNITED STATES PATENT OFFICE.

JAMES T. HALSEY, OF PHILADELPHIA, PENNSYLVANIA.

EXPANSIBLE-FLUID ENGINE.

SPECIFICATION forming part of Letters Patent No. 790,829, dated May 23, 1905.

Application filed September 7, 1904. Serial No. 223,595.

To all whom it may concern:

Be it known that I, JAMES T. HALSEY, a citizen of the United States of America, residing in the city and county of Philadelphia, in the 5 State of Pennsylvania, have invented a certain new and useful Improvement in Expansible-Fluid Engines, of which the following is a true and exact description, reference being had to the accompanying drawings, which form 10 a part thereof.

My invention relates to multiple-cylinder expansible-fluid engines, in which a group of cylinders are secured to the main shaft and rotate with it, while the pistons working in 15 said cylinders, and through them the cylinders, are coupled to a fixed crank; and the object of my present invention is to mitigate and largely overcome the lack of balance which is incident to such engines as heretofore constructed.

Essentially my invention consists in employing in such engines more than a single set of such cylinders and pistons and in so arranging the sets that the reciprocating parts 25 will as far as possible move simultaneously in opposite directions. A double set of engine-cylinders will usually be found most convenient, and in this case I arrange the similar cylinders and pistons of the two sets at an 30 angle of ninety degrees to each other.

In the drawings which illustrate an engine embodying my invention, Figure 1 is a cross-section on the line 1 1 of Fig. 2. Fig. 2 is a cross-section on the line 2 2 of Fig. 1. Figs. 35 3 and 4 are side elevations of the cylinders and pistons of the two sets, showing their relationship in position to the center of rotation. Fig. 5 is a section on line 5 5 of Fig. 1, and Fig. 6 is a section on line 6 6 of Fig. 1.

40 A is a casing inclosing the crank and cylinders and serving as a frame or support for the shaft, the crank-support, and the valve-boxes.

A' indicates the bearing for the shaft; A², 45 the bearing for the shaft supporting the crank.

A³ and A⁴ are the valve-boxes and bearings on opposite sides of the casings, A⁵ and A⁶ the entrance and exhaust ports for steam lead-

ing to valve-box A³, and A⁷ and A⁸ similar ports leading to valve-box A⁴. 50

B is a shaft supported in bearing A² and having at its inner end the disk B', from one side of which extends the crank B², a reduced end B³ of which extends into a bearing in the disk D, supported on a stud E⁷ of the cylinder-frame. In order to permit an angular adjustment of the crank to regulate the cut-off of the valves, an adjusting-arm C, with threaded segment C', is secured on the end of shaft B and engaged with a worm C², supported on a bracket A⁹ of the casing. 55

E is the engine-shaft, supported in bearing A' and, as shown, formed integral with the valve E' and with ports E², E³, E⁴, and E⁵, which open laterally, so as to register as the 60 valve turns with the ports A⁵ and A⁶ of the valve-box A³. The valve and shaft have secured to them the frame or spider E⁶, on which is formed the stud E⁷, already referred to, and through the right-angled arms of 65 which run continuations of the ports of the valve. To two opposite arms of the spider-frame are secured the cylinders G G', having ports G² G', which connect, as shown, with ports E³ and E⁵ of the spider. The other opposite arms of the spider carry oppositely-facing slide-guides H H', through which extend the ports E² E⁴, connecting through their 70 faces with the cylinder moving between the guides through ports G³ G'. 75

F' is a valve generally similar to valve E', but moving in valve-box A⁴, and around the shaft B, as shown, secured to it, is the frame or spider F⁶, the valve and spider being provided with ports F² F³ F⁴ F⁵, as in the case of 80 spider E⁶. The two spiders are arranged with their similar parts at an angle of ninety degrees to each other and are firmly secured together by bracing, such as disk I. The slide-guides of spider F⁶ are indicated at H² and H³, 85 and the cylinders secured to the other arms are marked G and G', as before. 90

J and J' are pistons moving in cylinders G and G' and connected together by their connection to a transverse cylinder J², having 95 slide extensions J³ J³ at its ends which move

in the slide-guides H H' or H² H³, as the case may be. These cylinders are slotted at the sides to give passage to crank B².

5 K K are pistons moving in cylinders J² J² and having transverse central bearings K' for the crank B².

In operation the steam entering through ports A⁵ and A⁷ and exhausting through ports A⁶ and A⁸ passes to and from each valve and 10 spider port and its connected cylinder or cylinder end in turn causing the pistons to reciprocate and the whole system to rotate, as the pistons can only reciprocate by moving around the crank B², and it will be seen by 15 reference to Figs. 3 and 4 that not only are the parts to some extent balanced by reason of their positions at right angles to each other, but that their shifting reciprocating movements are necessarily such that the center of 20 gravity of both sets of cylinders and pistons is on the average closer to the center of rotation than is the case with the center of gravity of either set.

The general construction of the engine described and shown apart from the utilization 25 of two sets of cylinders and pistons is substantially the same as the construction forming the subject-matter of my pending application for Letters Patent, filed February 13, 30 1900, and renewed March 17, 1904, Serial No. 198,657. Therefore I do not claim in this application other features than the balancing of the engine, as described.

Having now described my invention, what I claim as new, and desire to secure by Letters Patent, is—

1. An expandible-fluid engine having a fixed crank-pin and having two similar sets of rotating and reciprocating cylinders and pistons connected therewith as described and arranged with the similar parts of the two sets at right angles to each so as to effect a balance of the rotating and reciprocating parts. 40

2. An expandible-fluid engine having a casing for inclosing its movable parts provided with bearings on opposite sides for the main shaft and for a fixed crank shaft or support, said casing having also bearings on its opposite sides for rotating valve-plugs and inlet and outlet steam-passages leading thereto, in combination with a fixed crank, two similar sets of rotating and reciprocating cylinders and pistons working on said crank, rotating valve-plugs working in the bearings aforesaid, frames connecting the valve-plugs with the 45 cylinders and main shaft, said frames having ports connecting the ports of the valve-plugs with the cylinders and means securing the two sets of cylinders together so that the similar reciprocating parts of the cylinders and pistons of each set will be at right angles to each other and balanced in their movements. 50

JAMES T. HALSEY.
